Inventor:

I E Palmer

UNITED STATES PATENT OFFICE.

I. E. PALMER, OF ST. LOUIS, MISSOURI.

TACKLE-BLOCK.

Specification forming part of Letters Patent No. 25,978, dated November 1, 1859; Reissued September 8, 1863, No. 1,534.

To all whom it may concern:

Be it known that I, I. E. PALMER, of the city and county of St. Louis and State of Missouri, have invented a new and useful 5 Improvement in Tackle-Blocks and Pulleys; and I do hereby declare that the following is a full, clear, and exact description of the same, reference being had to the annexed drawing, making part of this specification, 10 in which—

Figure 1 shows a plan of the block and pulley combined, and Fig. 2 shows one side of the pulley, and Fig. 3 the other, and Fig. 4 a plan of block.

15 This my invention consists of a peculiar formation of the block and pulley and in a certain relative position of the said forms, when the two are combined, so that a rope or "fall" may be jammed in any required 20 position, thus securing the said rope or "fall" without tying it.

To enable others skilled in the art to make and use my said invention I will proceed to describe the construction and operation 25 thereof.

The drawing shows the block made in the form of a sphere, with a recess cut in one side of it, into which the "sheave" or pulley is introduced. This recess has a peculiar 30 form, which is shown at A; Fig. 4, and the

pulley or sheave is made with a circular groove at one end—as an ordinary sheave—and the other end is made of a plane cylinder form, as at B, after which a part of the lip which forms the circular groove is cut away, as at a, that is to say, a part of lip next the cylindrical end of the sheave, the said lip being thus made to form a kind of cam, as shown at Fig. 3. Now if the rope be drawn up and down upon a vertical or 40 horizontal plane the pulley will revolve freely in the block in either direction—but if the rope be drawn up to an angle, as indicated in red, then the moment it is let go it will be jammed between the block and 45 the pulley, by reason of the before described form of the block and pulley.

I lay no claim to the block and pulley as such; but

What I claim as my invention and desire 50 to secure by Letters Patent, is—

The form of the block in the inside, and the form of the pulley, when the two are combined and arranged substantially as described for the purpose specified.

I. E. PALMER.
